FREDRICK W. GORDON, OF PITTSBURG, PA., ASSIGNOR, BY MESNE ASSIGNMENTS, TO HIMSELF AND JAMES P. WITHEROW, OF SAME PLACE.

HOT-BLAST STOVE.

SPECIFICATION forming part of Letters Patent No. 278,234, dated May 22, 1882.

Application filed March 31, 1882. (No model.)

To all whom it may concern:

Be it known that I, FRED. W. GORDON, of Pittsburgh, Allegheny county, Pennsylvania, have invented certain new and useful Improvements in Hot-Blast Stoves, of which the following is a specification.

In the accompanying drawings, Figure 1 is a vertical section on line W, and Fig. 2 is a front elevation, part section, on line L.

10 This invention pertains to regenerative hot-blast stoves. It relates to the form of the roof of the shell, to a diffusion arrangement for the gas and air of combustion, to the construction of the roof of the chamber at the foot of the 15 regenerator-flues, and to means for altering the relative areas of the final uptake and down-take of the regenerator.

It consists of a roof-sheet joined to the top by a double miter, the arch of the roof-sheet being 20 parallel to the internal arches over the combustion-chamber and regenerator; of a perforated arch near the bottom of the combustion-chamber to separate the inlets of the gas and 25 air of combustion; of a chamber at the foot of the regenerator, with a perforated arched roof formed by the lower termination of regenerator-walls, and of a partition-wall in such chamber to divide said chamber and apportion 30 said perforations in the roof between the apartments.

A regenerative hot-blast stove of the type to which my invention pertains generally consists of a vertical cylinder constructed of plate-iron made air-tight against the usual pressures of hot blast, and provided with interior air and gas conduits, of brick or other refractory material, as hereinafter set forth. Such stoves are constructed as much as thirty feet in diameter, and designed to stand an internal air-pressure of about twenty pounds per square inch. Heretofore the roofs of such stoves have been made flat, and the proper strength secured by cross-beams of iron tied to the cylindrical portion of the shell. Such 45 a construction is expensive, untidy, and not over strong. Another common form of construction is the dome-shaped or hemispherical roof, in which the metal is distributed exactly right to meet the internal strains. This construction, however, requires that the metal be cut in forms involving much waste; that the

sheets be worked up in formers at great expense; that the punching and riveting be done with extraordinary care, and that any exterior attachments in the way of cleaning-doors 55 be fitted to spherical surfaces. It also involves a very awkward construction of the interior brick-work at the top.

In my improved stove-top construction a flat sheet is simply mitered to the cylinder, as 60 shown, thus presenting a semicircular contour to one view and a square contour to the other view. Flat riveted work only is involved, and a theoretical analysis of the strains, as well as practical experience with the stoves, proves 65 the construction to be correct. The interior brick arches, D, have their axes parallel with the axis of the miter-roof.

G is the gas-inlet and hot-blast outlet.

Q is the chimney-connection and cold-blast 70 inlet.

H is the combustion-chamber. The gases and air-blast move through the stove as usual.

Heretofore the air required for combustion has been admitted into the combustion-chamber in a stream, or at various points in the path of the gas, or in a row of jets from a blast-pipe in the combustion-chamber. By such means proper diffusion of the fluids has not been effected. In my construction I pass a 75 horizontal stream of gas over a perforated brick surface, through which the air is drawn by natural draft. The perforations cause the air to diffuse into the entire area of the gas stream as presented to the brick surface. 85

I is the brick surface, with perforations J distributed over its surface.

K is the air-admission valve. The diffusion caused by this means is early and perfect. Obviously the gas might be admitted under 90 the arch I and diffused into the air, which would in such case be admitted above the arch, the point being to separate the two incoming fluids by a horizontal surface, perforated so as to cause the under fluid to diffuse itself up 95 into the other fluid in streams fairly distributed over the entire separating-surface. The valve K being used as a blow-off valve when the stove is taken off blast causes the out-current of air to rush through the arch-ports J 100 and cleanse them from deposits of gas-dirt.

Heretofore the regenerator-walls of hot-

blast stoves have been borne by metal supports, or by piers and lintel-arches. The metallic supports give down under high heats, and the pier and lintel construction renders 5 the base of the walls complicated and expensive and obstructs the cleaning-chambers. I construct my cleaning-chamber with an arched ceiling sprung from the main and dividing walls, and pierce this ceiling with openings to 10 match the flues of the regenerator, whereby the flues are continuous, and of brick, clear to the cleaning-chamber. I erect the wall P under the arch O, to divide the cleaning-chamber and divert the currents of gas or blast, as 15 will be understood from the arrows. This wall bears no weight, and is removable, should it be desired to divide the regenerator differently, without disturbing the regenerator-walls. As shown in the drawings, the gas is forced by 20 wall P to confine its upward passage to the three sets of flues R, and it returns downward through the three sets of flues V. The expansion and contraction and friction in passage 25 of hot gases through flues often involves experimental changes in the flue area for the gases at different stages of their progress. Moving wall P one section to the right would give the gases four sets of flues in the uptake and three in the final downtake. This feature 30 of a removable non-supporting wall at the base of the regenerator can be embodied in

stoves with numerously subdivided uptakes and downtakes in the regenerator.

The wall P can be torn down and rebuilt at any desired point without disturbing any other 35 portion of the regenerator.

I claim as my invention—

1. The combination of a cylindrical main wall, a vertical dividing-wall, parallel roof-arches over the apartments formed by the dividing-wall, a cylindrical metal shell projecting on two opposite sides above said roof-arches, and a shell-roof sheet with the axis of its arch parallel to the axes of said roof-arches, joined to said shell by a double miter, substantially as set forth. 40

2. In a hot-blast stove, the combination of combustion-chamber H, opening G, forming hot-air outlet and gas-inlet, perforated brick surface I J, and opening K, forming the blow-off and inlet for air to the gas, substantially 45 as and for the purpose set forth.

3. The combination of the multiflue regenerator, having a base forming the perforated and arched ceiling of the base-chamber, and the non-supporting wall reaching from the floor to the roof of said chamber, substantially 50 as and for the purpose set forth.

FRED. W. GORDON.
